PRICE TICKET HOLDER

Filed Aug. 5, 1931

Inventor

PHILLIP HOPP.

By Perry H. Patterson

Attorney

UNITED STATES PATENT OFFICE

PHILLIP HOPP, OF NEW YORK, N. Y.

PRICE TICKET HOLDER

Application filed August 5, 1931. Serial No. 555,240.

This invention relates to new and useful improvements in display devices, and more particularly it pertains to a price ticket holder especially adapted for use in connection with steel shelving.

Steel shelving presents problems in the attachment of price ticket holders not present in wooden shelving because of the fact that such shelving is generally constructed of relatively thin sheet metal and to lend strength and finish thereto, the shelves are generally formed with a flange which extends around one or more edges of the shelves, and which depends or extends downwardly therefrom. Such a construction presents a shelf in which the forward edge is of a width which is greater than the thickness of the material from which the shelf is formed as distinguished from wooden shelving in which the width of the forward edge of the shelf is substantially equal to the thickness of the material from which the shelf is made.

It is the primary object of the present invention to provide a price ticket holder which is especially adapted for use in connection with shelves formed of sheet metal, and particularly such shelves as are formed with a flange depending from the forward edge thereof.

It is a further object of the invention, so to construct a price ticket holder that it may be readily attached to, and removed from sheet metal shelving of the aforementioned character, and which will be securely retained in operative position upon the shelf.

A still further object of the invention resides in a novel construction whereby the holder is retained in position upon a shelf without the use of separate fastening elements.

In some forms of metal shelving, the flange which depends from the forward edge of the shelves is bent rearwardly and upwardly with the upwardly bent portion spaced from the body of the flange, and it is an object of this invention to provide a price ticket holder which may be employed in connection with this type of shelving as well as with the types aforementioned.

With the aforementioned, and other ob-

jects in view, reference will be had to the accompanying drawing, wherein:

Figure 1, is a perspective view of a complete device constructed in accordance with the present invention,

Figure 2, is a vertical sectional view taken through a metal shelf showing the manner of attachment of a price ticket holder constructed in accordance with the present invention,

Figure 3, is a vertical sectional view illustrating a modified form of the invention, and;

Figure 4, is a perspective view of the shelf engaging member of that form of the invention illustrated in Figure 3.

Referring more specifically to the drawing, it will be noted that the device comprises a resilient attaching member 5 and a ticket carrying panel or similar member 6.

The resilient attaching member 5 is preferably formed from spring metal which is bent upon itself as at 7 to substantially U-shaped cross sectional form and providing two spaced walls 8 and 9.

The wall 8 is formed along its upper edge with a right angular extension 10 which forms a foot for engagement with the under face of a shelf or the like 11. The wall 9 is formed along its upper edge with an inwardly disposed bead 12 which preferably extends throughout the length of the upper edge of the wall. As best illustrated in Figures 2 and 3, the wall 9 is slightly wider than the wall 8 and this construction throws the bead 12 to a position slightly above the plane of the foot or right angular extension 10 and this distance is substantially equal to the thickness of the metal from which the shelf 11 is formed.

By this construction it will be apparent that when the device is engaged with the end of a shelf of the type illustrated in Figure 2, the depending flange 13 of the shelf will be received between the walls 8 and 9 of these resilient clips. In this position, the foot 10 engages the under surface of the shelf 11 and the bead 12 engages the upper face of the shelf 11 at the forward edge thereof, with the depending flange portion 13 of the

shelf positioned between the walls 8 and 9 of the resilient clips.

Engagement of the bead 12 with the upper edge of the shelf 11, places the resilient member 5 under tension and such tension serves to retain the bead 12 in engagement with the shelf and also the foot 10 in engagement with the under surface of the shelf with sufficient holding action to retain the device in place thereon.

The ticket carrying member 6 may be of any desired form and in the present instance it consists of a panel like member provided with ticket retaining flanges 15 upon its opposite side and lugs 16 upon its end which serve to position the tickets. Cut out portions 17 are provided to facilitate placing and removing the tickets therefrom. The ticket carrying element 6 may be attached to the resilient clip 5 by integral extensions 18 which are bent around the ends of the wall 9 of the resilient member 5.

In Figures 3 and 4, there is illustrated a slightly modified form of the invention and the device shown in these figures is especially adapted for use in connection with shelves in which the depending flange 13 is bent rearwardly and upwardly as indicated at 20 in Figure 3. In this form of the device, the resilient clip 5 is formed along its line of fold with an enlarged portion 25 which is of sufficient dimension to receive the portion 20 of the shelf without unduly springing the resilient clip and permits of the resilient action of said clip firmly gripping a shelf of the second mentioned type.

Thus it will be apparent that the present invention provides a new and improved ticket holding device for use with metal shelving which is so constructed and arranged as to be securely retained upon a metal shelving.

While the invention has been herein illustrated in a preferred form, it is to be understood that it is not to be limited to the specific construction herein shown and that it may be practiced in other forms without departing from the spirit thereof.

Having thus described the invention, what is claimed as new and what it is desired to secure by Letters Patent of the United States, is:

1. A price ticket holder for use with metal shelving comprising a resilient shelf engaging member, U-shaped in cross sectional form, a shelf engaging bead formed on one leg of the shelf engaging member, a shelf engaging foot carried by the other leg of the shelf engaging member, said bead and foot co-operating with a metal shelf to retain the shelf engaging member on a shelf, and ticket carrying means carried by said shelf engaging member.

2. A price ticket holder for use with metal shelving of the type having a depending flange, said holder comprising a resilient

member adapted to embrace said depending flange, a bead formed on said resilient member and adapted for engaging with a shelf, a foot formed on said resilient member for engagement with the under face of a shelf and co-operating with said bead to retain the resilient member on a shelf, and ticket carrying means mounted on said resilient member.

3. A display card holder for use with steel shelving comprising a resilient member, a bead formed on the resilient member, a foot formed on said resilient member, said bead and foot being spaced from each other a distance substantially equal to the thickness of the material of the shelf to which the device is to be attached and adapted to engage opposite faces of the shelf, and ticket carrying means carried by said resilient member.

4. A device of the character described comprising a resilient member formed of sheet metal folded upon itself to provide two substantially parallel spaced walls, a bead extending along the free edge of one of said walls, a right angular extension forming a shelf engaging foot extending along the free edge of the other of said walls, said bead and foot co-operating to retain the resilient member upon a shelf under its own resiliency, and a ticket carrying panel carried by said resilient member.

5. A device of the character described comprising a resilient member formed of sheet metal folded upon itself to provide two substantially parallel spaced walls one of which is narrower than the other, a bead extending along the free edge of the wider of said walls, a right angular extension forming a foot, extending along the free edge of the narrower of said walls, said bead and said foot forming a shelf engaging and clamping means, and a card or ticket carrying member mounted on said resilient member.

6. A device of the character described comprising a resilient member formed of sheet metal folded upon itself to provide two substantially parallel spaced walls one of which is narrower than the other, a bead extending along the free edge of the wider of said walls, a right angular extension forming a foot, extending along the free edge of the narrower of said walls, said bead and said foot forming a shelf engaging and clamping means, and a card or ticket carrying member mounted on said resilient member, said card or ticket carrying member having integral extensions adapted for bending around the ends of one of the walls of the resilient member to secure the card or ticket carrying member to the resilient member.

7. A price ticket holder especially adapted for use with metal shelving having a depending forward flange, and comprising a resilient sheet metal member bent upon itself to provide two parallel walls one of which is wider than the other, an inwardly disposed

bead formed on the wider of said walls and
adapted for engagement with a shelf at the
line of bend of the depending flange thereof,
a right angular extension formed on the nar-
rower of said walls and adapted to engage the
under face of a shelf at a point behind the
depending flange thereof and thereby grip
the shelf between said bead and said foot, and
a ticket carrying panel carried by said resil-
ient member.

10 In testimony whereof I affix my signature.
PHILLIP HOPP.
